UNITED STATES PATENT OFFICE.

ROGER STEPHENS, OF WESTFIELD, NEW JERSEY, ASSIGNOR TO SNYDER & BLACK, INCORPORATED, OF NEW YORK, N. Y., A CORPORATION OF NEW YORK.

DESIGN FOR A DISPLAY STAND FOR TIRES.

Application filed October 17, 1923. Serial No. 7,528. Term of patent 3½ years.

To all whom it may concern:

Be it known that I, ROGER STEPHENS, a citizen of the United States, residing at Westfield, in the county of Union and State of New Jersey, have invented a new, original, and ornamental Design for Display Stands for Tires, of which the following is a specification, reference being had to the accompanying drawing, forming part thereof, wherein the figure is a perspective view of a display stand for tires, showing my new design.

I claim:

The ornamental design for a display stand for tires as shown.

Signed at New York, borough of Manhattan, in the county of New York and State of New York, this 15th day of October, 1923, before two subscribing witnesses.

ROGER STEPHENS.
